UNITED STATES PATENT OFFICE.

JAMES C. DALEY, OF CHICAGO, ILLINOIS, ASSIGNOR TO JEFFERSON ELECTRIC MFG. CO., OF CHICAGO, ILLINOIS, A CORPORATION OF ILLINOIS.

MEANS FOR RECONDITIONING RADIOTUBES.

Application filed August 10, 1925. Serial No. 49,468.

This invention relates to means for reconditioning radio tubes and the like and pertains more especially to the thoriated tungsten filament. These filaments, as well as others of this type, with the pure tungsten filaments are subject to various troubles or misuses which I have outlined as follows:

I find that the period over which tubes of this sort will give efficient service is limited. They are dependent for proper operation on a high degree of vacuum. The emission is paralyzed by excessive filament voltages and apparently becomes exhausted from continued use.

Through continued use occluded gases are liberated which cause a high surface resistance and reduce the electronic emissivity.

Tube deterioration begins with the first instant's use and within a comparatively short time a noticeable decrease in plate current and amplification often takes place, which is made apparent by the radio set giving less volume and poor quality. The average radio owner usually increases the filament current in an effort to force the tubes to perform as they should. This generally hastens the tube's demise and gives unsatisfactory reception. Excessive filament current may even burn out or completely destroy the tube long before its useful life would under normal conditions, be reached. These tubes are relatively expensive and frequent replacement is undesirable. One weak tube in a multiple tube set will keep the entire set from functioning properly and increasing the filament currents to compensate for lack in volume, may soon impair the balance of the tubes.

My present invention is designed to recondition the tube and thus retard deterioration or loss of effectiveness due to any one or any combination of the foregoing causes, and the objects of my present invention are the provision of a generally improved and simplified device that may be economically produced.

Primarily, I provide for imposing, first, a relatively high voltage across the filament, and following this with a lower voltage. The greater voltage drives the gases out of the filament—and reduces the surface resistance thus increasing the electronic emissivity. It is possible also that some of the thorium is brought to the surface in the form of a film. The lower voltage is then

applied to anneal the filament wire and leave it in a proper tensile condition, not brittle or paralyzed. Where it is paralyzed, it seems to de-paralyze it and bring it back to its proper tensile condition so that by the treatment which I provide, the tube is properly reconditioned whether paralyzed or exhausted or a combination of the two.

I provide for using an alternating or pulsating current which I find is highly desirable for this purpose. The intervals between the pulsations seem to provide a cooling or stabilizing effect upon the filament which does not seem to be secured where direct or uni-directional current is employed. Furthermore, the possibility of injuring the filament in the treatment thereof is reduced.

In the drawings:

Fig. 1 is a top plan view of one embodiment of the invention;

Fig. 2 is a side elevational view of the same;

Fig. 3 is a horizontal section taken on the line 3—3 of Fig. 2;

Fig. 4 is a vertical section taken on the line 4—4 of Fig. 1;

Fig. 5 is a detailed section on line 5—5 of Fig. 1;

Fig. 6 is a detailed section taken on the line 6—6 of Fig. 1; and

Fig. 7 is a circuit diagram of the invention.

The device selected for illustration comprises a container 5 of generally rectangular formation with an open top and bottom. This container 5 may be formed of sheet metal or any other suitable or preferred material, the free ends of the stock making a lap joint at 6 and adapted to be fastened together along said joint as by means of rivets 8.

The open bottom of the shell 5 is closed by a bottom member 10 which may also be of sheet metal or other suitable material and has an upstanding flange 12 surrounding the lower edge of the container 5, the bottom 10 being adapted to be secured to the lower edge of the container through this flange as by means of rivets 14.

Underlying the bottom 10 is a base member 15, the margin 16 of which is downset at 17 to provide a surrounding supporting ledge and turned up obliquely at 18 therefrom. Within the margin 16 the base member 15 has protuberances 19 pressed up out of the surface thereof and adjacent same the

squarely against the inner or bottom wall of the said socket. The operator then uses a hammer, striking the outer plug in the direction of the length of the axle whereby the wheel is jarred loose from the axle and the key thereof and may be quickly removed.

Having described the invention what is claimed is—

A device adapted to be used for removing a wheel from an axle upon which it is keyed comprising a body provided at its opposite ends with alined sockets of different sizes, and anvil plugs fitting in the sockets.

In testimony whereof I affix my signature.

CASH A. CLEMONS.

properly engage and press firmly against the desired tube contacts upon insertion of the same into the socket. As with the socket 35, the opposite end of the spring 60' is secured to the panel 28' by the stud 62', which stud 62' passes through the panel, pivots a switch arm 63' and electrically connects the spring 60' with said arm 63'. The arm 63' has, as before, a limited pivotal movement about the stud 62' as an axis and between a pair of stop pins 64' secured to the panel 28'. At its outer end the arm 63' has a terminal contact 65' and an insulating knob or fingerpiece 68' for swinging the knob into the desired position. Secured to the panel 28' in the path of travel of the contact 65' are a high voltage contact 70' and a low voltage contact 72', one of these contacts underlying the contact 65' at each of its 20 limits of pivotal or swinging movement.

As before, the low voltage contact 72' may be raised or headed slightly (Fig. 6) so that as the arm 63' is swung over the same the contact 65' will be sprung into engagement therewith, but the high voltage contact 70' is preferably recessed (Fig. 5), so that upon swinging the arm 63' thereover depression of the arm 63' is necessary to bring the contact 65' into contact with the terminal contact 70'. The purposes of this have already been explained in connection with the socket 35.

I preferably employ alternating or pulsating current, and for applying the desired voltages to the tube connectors, I provide within the container 5 a suitable transformer 80. The transformer 80 may be of the type more fully disclosed in the co-pending application of Morris M. Fulton, Serial No. 737,958, filed September 15, 1924, or it may be of any other suitable or preferred type. As shown in the circuit diagram of Fig. 7, it comprises a primary winding 82, a secondary winding 83 and suitable core 84. 40 Suitably insulated conductors 85 supply the primary winding 82 with alternating current, said conductors 85 extending out through an insulating bushing 86 mounted in one side of the container 5 and being provided at their free end with a suitable plug or connector 87 for quick connection and disconnection with an "Edison" or other outlet.

Referring further to the diagram of Fig. 7, a conductor 90 connects one end of the secondary 83 with one pair of terminal contacts of the two tube sockets, for example, the contacts 56 and 56', and this conductor forms a common connection for the "high" and "low" of both sockets. A conductor 92 connects the opposite end of the secondary winding 83 with the "high" contact 70 for the socket 35. The "low" contact 72 for the socket 35 is connected to the secondary 83 by means of a conductor 93, it being apparent that the voltage between the connection

of the conductor 90 with the secondary, and the connection 93 therewith is less than the voltage between the conductor connections 90 and 92. The "high" contact 70' for the socket 36 is connected to the secondary by means of a conductor 95 and the low contact 72' for said socket is connected to the secondary by means of a conductor 96, it again being apparent that the voltage between the conductor connection 90 and 95 is greater than the voltage between the conductor connection 90 and 96 with the secondary. The ratio between these voltages in a particular device which I have found suitable for the purpose contemplated, is generally in the order of 15 to 8 for the socket 35 and 10 to 5 for the socket 36. This, of course, may and will vary with different adaptations.

In use, the tube is placed in its corresponding socket with the filament contacts in proper engagement with the contact arms 56 and 60 or 56' and 60' thereof. The corresponding switch arm 63 or 63' is then switched onto "H" contact and held manually for 45 seconds. This high voltage across the filament drives the occluded gases out and brings the thorium to the surface of the filament and conditions the same for further electronic emission. Upon the expiration of 45 seconds on the "H" contact, the switch arm is swung to the corresponding "L" contact and is left there for 10 minutes. This low voltage current across the filament anneals the filament and prevents brittleness or paralyzation, and brings the filament to proper condition for further use. The tube is then removed and is ready for further use. It may be tested before and after the reconditioning treatment to determine the degree of improvement, and where still further improvement is required, the tube may be additionally treated or treated over for a less period of time, depending upon the condition thereof.

The device is simple and compact and its use is quick and effective. The transformer coils, leads and connections, may be sealed within the container by a suitable insulating compound (not shown). The device is self-contained and the container performs the additional function of supporting the tubes without danger of short-circuiting and the excessive application of a high filament voltage in treating the tube is provided against.

The cover 25 may be detachably secured to the container as by the cooperation of indentations 100 pressed into the marginal flange 27 thereof (Fig. 4) with indentations 102 pressed into the upper edge of the wall of the container 5. These indentations may be formed for example by slitting the cover flange 27 and the adjacent edge of the container wall and pressing the lower lip or side freed by the slit inwardly, so that the in-
